Primary Examiner — Maria J. Edwards(74) *Attorney, Agent, or Firm* — Venable LLP(57) **CLAIM**

The ornamental design for a glove, as shown and described.

DESCRIPTION

FIG. 1 is a front perspective view of a glove, according to the present design.

FIG. 2 is a front view thereof.

FIGS. 1-2 show a right hand glove or portions of a right hand glove. The left hand glove and the portions of a left hand glove, which are not depicted in the drawings are the mirror images of FIGS. 1-2.

The circles shown on the pads on the front side of the glove represent holes that extend through the outer layer of the pads.

Broken lines are used to illustrate portions of the glove that form no part of the claimed design.
